UNITED STATES PATENT OFFICE.

EDWIN V. HEAFORD, OF DENVER, COLORADO.

CALENDAR.

1,162,606.

Specification of Letters Patent.

Patented Nov. 30, 1915.

Application filed January 30, 1915. Serial No. 5,260.

To all whom it may concern:

Be it known that I, EDWIN V. HEAFORD, a citizen of the United States, residing at Denver, in the county of Denver and State 5 of Colorado, have invented new and useful Improvements in Calendars, of which the following is a specification.

This invention relates to calendars and more particularly to perpetual calendars.

10 The principal object of the invention is to provide a calendar constructed in such manner that the member carrying indicia representing the days of the week may be readily shifted so as to accord with the days of 15 the month or to conceal certain of the days of the month.

Another object of the invention is the provision of a calendar having means for displaying the indicia designating the name of 20 the month and means for concealing certain of the indicia indicating the days of the month, as where the calendar is used for February or months having only thirty days.

25 Another object of the invention is to provide a calendar of this character which is formed in such manner that it produces an article holder.

Further objects of the invention will appear as the following description is read in 30 connection with the accompanying drawing, which forms a part of this application, and in which:—

Figure 1 is a side elevation showing the 35 invention applied to a combined perpetual calendar and pencil holder. Fig. 2 is a longitudinal sectional view taken therethrough. Fig. 3 is a similar section taken at right angles to Fig. 2. Fig. 4 is a horizontal section taken on the line 4—4 of Fig. 1. Fig. 5 is a similar section on the line 5—5 of Fig. 1. Fig. 6 is a similar section on the line 6—6 of Fig. 1. Fig. 7 is a similar section 40 on the line 7—7 of Fig. 1. Fig. 8 is a plan 45 view of the tube blank. Fig. 9 is a plan view of the clip blank. Fig. 10 is a perspective view showing a modified arrangement of the calendar. Fig. 11 is the side elevation of the modified form of my invention 50 as applied to an ink well or paper weight.

Referring more particularly to the drawing, 1 represents an elongated tube constructed from a single sheet of material, 55 such as is shown in Fig. 8, and provided at its lower end with an outwardly extending

externally milled rib 2 which facilitates the holding of the tube, as will be hereinafter described. The tube is also provided with an annular externally extending rib 3 which 60 retains the clip blank or sleeve 4 in position, as will be hereinafter described. Intermediate the ribs 2 and 3 the blank is formed with a plurality of inwardly projecting tongues or fingers 5 which have sufficient 65 resiliency when bearing against the sides of the pencil to hold the same in properly adjusted position within the tube.

Immediately above the rib 3 and approximately at a central point between said rib 70 and the upper edge of the tube 1 there is formed in the blank a plurality of longitudinally extending ribs or ridges 6, seven in number to be exact, which produce seven 75 spaces 7 for the reception of indicia showing the days of the month. These ribs are all provided with depressions 8 arranged in rows transversely of the blank and intermediate the indicia just mentioned.

Slidably and rotatably mounted upon the 80 top of the tube is a sleeve 9 having an equal number of ribs or raised ridges 10 with the 85 ridges 6 of the tube 1. These ridges are of sufficient size to receive the ridges 6 and have their lower ends bent inwardly to produce a small ear 11 for engagement with the 90 depression 8 in the ribs 6. The upper end of the sleeve 9 is provided with an annular raised and milled rib 12 which insures a 95 positive grip for rotating or sliding the sleeve. Between the ribs 10 are formed 100 spaces 13 which receive indicia showing the days of the week. This sleeve may be raised above the ribs 6 and rotated so as to change the days of the week to correspond with the days of the month shown between the ribs 6 or may be moved downwardly over the ribs so as to conceal the monthly indicia as the weeks of the month go by.

Surrounding the tube immediately above the rib 3 and rotatably mounted thereon is an annular strip 14 which is provided with lateral offset abutting ends 15 which project radially and form a detent for engagement 105 with the internal grooves of the clip blank 4. This clip blank is curled into tubular form and surrounds the strip 14 and the tube 1 being held against longitudinal displacement by the annular rib 3 which fits into a correspondingly formed groove 16 produced adjacent the lower edge of the blank 4. This inner groove, of course, pro-

duces an exterior rib which is milled, as shown at 17, to facilitate turning the blank upon the tube 1, as will be hereinafter described. The strip 14 is divided up into twelve spaces 18 in which the names of the months are placed in abbreviated form and on the line between each space there is made an opening 19 for the insertion of a pin or other similar tool by which the strip may be revolved independently of the clip sleeve. The indicia on the strip 14 is exposed through an opening 20 formed in the clip sleeve and the clip sleeve is held against accidental rotation on the tube 1 by means of the grooves 21 formed in an extension 22 which fits over the ribs 6, the grooves 21 partially receiving the ribs and the clip sleeve being arranged so that when turned the rib 6 will snap into the grooves, as will be readily understood. The extension 22 as shown is provided with an opening through which the numbers 29, 30 and 31 of the monthly indicia may be exposed when desired, or any of these numbers may be covered by the extension, as will be readily understood. Projecting from and integrally formed with the lower end of the blank 4 is a clip 23 which is adapted to engage over the outer pocket wall for securing the holder in position in the pocket, and, as shown, this clip is formed with off-sets 24 and 25 which form shoulders against which the edges of the strip 14 abut, thus preventing relative longitudinal movement of these parts.

In the modification shown in Fig. 10, the calendar is applied to an ink well or paper weight which comprises a base 1 and a standard 2 upon which the tube 26, cap sleeve 27 and the equivalent of the clip sleeve 28 minus the clip is mounted. In this instance the sleeve 28 is, of course, devoid of the clip but operates in a manner similar to

the clip sleeve 4, as does the cap sleeve 27 with relation to the tube 26. The daily indicia, of course, may show more than one week and in this instance the names of the months are arranged horizontally instead of vertically of the strip, surrounded by the sleeve 28. In other respects, the parts are identical with that disclosed in Fig. 1 except that they are on a larger scale and the tube 1 is supplied with any suitable means for securing it to the standard rising from the base.

In the claims where the tube is referred to as an article holder it is to be understood that I not only contemplate mounting the tube upon an article such as an ink stand or paper weight but that the tube is adapted to retain a pencil, pen or other similar device.

In turning or sliding the sleeve 9 or the sleeve 4 with the right hand the other hand may be used to hold the tube 1 against turning and the milled rib 2 is placed upon the tube to insure a firm grip.

What is claimed is:—

In a calendar, a tube adapted to hold an article and carrying indicia showing the days of the month, a sleeve slidably and rotatably mounted upon the tube and carrying indicia showing the days of the week, a sleeve rotatably mounted upon the tube and showing the names of the months, and an apertured sleeve surrounding the last-named sleeve and rotatable independently, said apertured sleeve having means to conceal certain of the monthly indicia.

In testimony whereof I affix my signature in presence of two witnesses.

EDWIN V. HEAFORD.
